ILLUMINATED PORTABLE WRITING BOARD

Carl W. Raabe, Sioux Falls, S. Dak.

Application March 25, 1941, Serial No. 385,175

9 Claims. (Cl. 240—6.4)

This invention relates to an illuminated portable writing board and it is an object of the invention to provide a device of this kind which is particularly intended to be used by meter readers, truck checkers, etc.

It is also an object of the invention to provide a board of this kind having associated therewith means whereby the board may be effectively illuminated to facilitate its use in the dark, together with means for throwing a ray of light in advance of the user so as to permit discernment of car numbers or other data to be recorded on a writing sheet on the board.

The invention consists in the details of construction and in the combination and arrangement of the several parts of my improved writing board whereby certain important advantages are attained, as will be hereinafter more fully set forth.

In order that my invention may be the better understood, I will now proceed to describe the same with reference to the accompanying drawing, wherein:

Figure 1 is a view in top plan of an illuminated portable writing board constructed in accordance with an embodiment of my invention;

Figure 2 is a fragmentary view in bottom plan of the upper portion of the board as herein comprised;

Figure 3 is a detailed sectional view taken substantially on the line 3—3 of Figure 2;

Figure 4 is a fragmentary detailed sectional view taken substantially on the line 4—4 of Figure 2; and

Figure 5 is a diagrammatic view illustrating the lighting circuits as herein embodied.

As disclosed in the accompanying drawing B denotes a portable writing board of desired dimensions and which is provided at one end portion with a conventional type of clamp C for holding a sheet of writing paper or the like in place upon the board. The detailed construction of the board B and clamp C forms no part of the present invention, although it is to be stated that it is preferred in practice that the board B have its marginal portions formed in a manner to eliminate the liability of cutting hands and scratching surfaces.

The clamp C is positioned at what is termed the top of the board B and secured to the under surface of the top portion of the board B is a relatively large plate 1. This plate 1 is held to the under surface of the board B by the same fastening means 2 for holding the clamp in position upon the board. This means 2, as herein dis-

closed, comprises a screw inserted from above through a member of the clamp C and through the board B and plate 1 with holding nuts threading upon the screws and co-acting with the outer face of the plate 1. The plate 1 is of a length to extend slightly beyond the upper margin of the board B and the opposite ends of the plate 1 are defined by the outstanding flanges 3 substantially at right angles to the plate 1.

The plate 1 is positioned at substantially the transverse center of the board B and the flanges 3 provide mountings for the elongated casings 4 each of which carrying the usual dry batteries 5 and wherein the circuit in which each set of dry batteries 5 is interposed is under control of a conventional switch 6. The outer or top flange 3 is provided with an opening 7 which is defined by an inwardly disposed socket member 8, the inner face of which being polished so that said socket member serves as a reflector. Threaded or otherwise disposed through the base wall of the socket 8 is the base or plug 9 carrying an incandescent bulb 10 which is substantially housed within the socket 8. The inserted end of the base or plug 9 has a conventional contact, as at 10', with the adjacent battery 5 within the casing 4 in substantial alignment with the opening 7. When the switch 6 associated with this particular casing 4 is in closed position the bulb 10 will function, resulting in the creation of a ray or beam of light which can be readily used in the dark or after nightfall in reading numbers on railroad cars or meters, house numbers, etc.

The top or outer flange 3 of the plate 1 is provided with a second socket 11 opening out through said upper or top flange 3 and which is provided with a base 12 for electrical connection, as at 14, in a well-known manner with the outer battery 5 within the second casing 4. Fitting within the socket 11 for electrical contact with the base 12 of the socket 11 is a plug 15 from which leads a conductor 16. This conductor 16 is in electrical connection with an angularly and inwardly disposed arm 17 of a material conductive of electricity and which is in continuation of an elongated and substantially rigid conductor arm 18. The angular arm 17 is snugly inserted within an insulating sleeve 19 which closely fits within an end portion of an elongated tubular member 20. This member 20 is disposed transversely of the plate 1 and is positioned immediately adjacent to the upper or top flange 3. This member 20 is secured in place by soldering or in any manner preferred, and as herein disclosed is also

of a length to extend a distance beyond the opposite sides of the plate 1.

The arm 18 is a conductor leading to one of the contacts for a lamp socket member 21 in which is received, in a conventional manner, the 5 base of an incandescent bulb 22. The socket 21 is disposed substantially at right angles to the arm 18 and in a direction toward the board B.

The second contact of the socket 21 has in 10 electrical connection therewith an elongated conductor arm 23. This arm 23 is also substantially rigid and the two arms 18 and 23 diverge away from the socket 21. The end portion of the arm 23 remote from the socket 21 is provided with an inwardly disposed and angularly related arm 24 which carries a plug 25 which is insertible within a socket 26 fixedly mounted within the end portion of the member 20 remote from the end into which the arm 17 is received. This arm 23 constitutes a grounding line for the circuit in 15 which the socket 21 is interposed. The end portion of the arm 23 adjacent to its arm 24 is selectively received within the notches 25 provided in the adjacent end of the member 20 so that the arms 18 and 23 may be held in a position to maintain the socket 21, together with its bulb 22, in different positions with respect to the board B, as may be preferred by the user.

It is to be pointed out that the arms 18 and 23 in addition to constituting conductors for the electric circuit for the socket 21 also constitute supporting means for said socket 21 which is carried thereby.

As is particularly illustrated in Figure 2, the upper or outer ends of the casings 4 have slip engagement over the socket members 8 and 11 while the inner or lower end portions of these casings 4 are partially received within the semi-circular recesses 26 provided in the outer longitudinal margin of the inner or lower flange 3. The adjacent end portion of each of the casings 4 is provided therearound with a continuous channel 27 into which the marginal portion of the flange 3 defining a recess 26 is received, thus providing an interlocking means to facilitate the maintaining of the casing 4 in working position.

The casings 4 are further held in applied position by a cap strip 28 which contacts the outer longitudinal edge of the inner or lower flange 3 and is provided with the suitably positioned semi-circular recesses 29 in each of which is received an end portion of a casing 4. The strip 28 at its longitudinal center carries the laterally directed spring arm 30 which passes through a suitably positioned opening 31 in the inner or lower flange 3, whereby the strip 28 is held in position, yet can be readily removed when desired.

From the foregoing description it is thought to be obvious that a writing board constructed in accordance with my invention is particularly well adapted for use by reason of the convenience and facility with which it may be assembled and operated.

I claim:

1. In a portable writing board, a board body having a top, a plate secured against one side of the board at the top thereof, the top and bottom portions of the plate having outstanding flanges, an elongated casing bridging the space between the flanges and supported thereby, said casing being adapted to house a battery, an electric current conducting means carried by one of the flanges for connection with a battery within the casing, socket members carried by the said one of the flanges, an electric illuminating member,

elongated supporting arms for said member diverging therefrom, plugs carried by the end portions of said diverging arms insertible within the said sockets, said diverging arms forming current conductors, and an electrical connection between one arm and one of the socket members for connection with one side of the battery, the second socket member and the other side of the battery being grounded to the plate.

2. In a portable writing board, a board body having a top, a plate secured to one side of the board at the top thereof, outstanding flanges carried by the plate at the top and bottom edges thereof, a casing interposed between and supported by the flanges, said casing being designed to house an electric battery, a socket member carried by one of the flanges and extending into the casing for electrical connection with a battery within the casing, and an illuminating member in electrical connection with the socket.

3. In a portable writing board, a board body having a top, a plate secured to one side of the board at the top, outstanding flanges carried by the plate at the top and bottom edges, a socket carried by the top flange, a battery casing having one end joined to the socket and having its other end coupled to the bottom flange, said socket being in electrical connection with one side of a battery housed in the casing, an electric incandescent lamp, and supporting means for said lamp providing an electrical connection between the other side of the battery and one side of the lamp and an electrical connection between the other side of the lamp and the socket.

35 4. A portable writing board as set forth in claim 3, in which the said one end of the battery casing is detachably connected with the socket and the coupling between the other end of the casing and the bottom flange comprises a member detachably secured to the bottom flange and having a recess coacting with a recess in the bottom flange to form an opening in which the casing is held.

40 5. In a portable writing board, a board body having a top, a plate secured to a side of the board at the top, top and bottom spaced flanges carried by the plate, means at opposite edges of the plate at the top forming oppositely directed current conducting sockets, an incandescent lamp holding socket, a pair of current conducting arms upon the side of the board opposite the plate and connected at one end with and supporting the lamp socket, the other ends of said arms being each mounted in one of the first sockets to turn therein on an axis extending transversely of the board whereby the lamp socket may be moved toward and away from the adjacent side of the board, one of said other ends of the arms being electrically insulated from the socket in which it is mounted, the ends 45 of the arms connected with the lamp socket being electrically insulated for electrical connection with opposite sides of an incandescent lamp mounted in the lamp socket, a battery casing secured between and electrically connected with one of said flanges, current conducting means electrically connected with that arm having its end insulated from the socket in which it is mounted and adapted for electrical connection with one end of a battery in the casing, and means for electrically connecting the other end of the battery with the casing whereby a closed 50 electrical circuit will be set up from one side of the battery through the casing, plate, one arm to the lamp socket, and back through the other

55 60 65 70 75 80 85 90 95 100

arm and said current conducting means to the other side of the battery.

6. A portable writing board as set forth in claim 5, with means adjacent to one of the said opposite sockets providing selective stops for engagement by the adjacent arm on being turned, to maintain the arms and lamp socket in a position of adjustment.

7. In a portable writing board, a board body having a top, a plate secured to one side of the board at and projecting above the top thereof, top and bottom spaced flanges carried by the plate, means forming a pair of current conducting sockets in the angle between the top flange and plate and aligned on an axis extending across the plate and disposed above the top of the board, a pair of current conducting arms upon the other side of the board from the plate and each having a portion extending across the top of the board and transversely of a socket and an inturned terminus forming a trunnion extending into the adjacent socket, the trunnion forming termini being turnable in the sockets and one being electrically insulated from its socket and the other being electrically coupled with its socket, an electric lamp socket having the other ends of the arms electrically connected therewith but electrically separated from one another for electrical connection with the two sides of an electric lamp in the lamp socket, the lamp socket being arranged to direct light from a lamp therein toward the board and the arms being movable to move the lamp socket toward and away from the board, a battery casing mounted between said flanges, means for establishing an electrical connection between the casing and one side of a battery therein, and means coupled with but electrically insulated from the casing adapted to form an electrical connection between the other side of the battery and the said one insulated arm terminus.

8. A portable writing board as set forth in claim 7, in which the one of the pair of sockets

with which the said other terminal is electrically connected has edge notches in which the board edge crossing portion of the adjacent arm may be selectively engaged and held upon movement of the arms.

9. In a portable writing board and in combination with a board body having a top edge, a metallic plate secured against one side of the body at said top, top and bottom flanges extending from the plate away from the board body, the flange at the top having two sockets extending toward the bottom flange, the bottom flange having a pair of edge recesses therein, a pair of tubular battery casings extending between the flanges and each having a socket frictionally engaged in one end, each casing having its other end disposed in a recess, means lying across the casings and secured to the recessed flange securing the casings in the recesses, one of said sockets having an incandescent lamp base receiving means, one side of said lamp being electrically connected to a battery in the adjacent casing through the casing and the other side of the lamp being directly in contact with the other side of the battery, an electric current conductor secured at one end in the other socket for electrical connection with one side of a battery in the adjacent casing, the other side of the last battery being electrically connected with the enclosing casing and with the plate, an incandescent lamp socket, a pair of current conducting arms each having one end electrically connected with one side of the lamp socket, the other ends of the arms being pivotally coupled with the top of the plate, the arms swingingly supporting the lamp socket on the other side of the board from the plate, and one of said arms being insulated from the plate but electrically connected with the other end of said current conductor and the other arm being in electrical connection with the plate for completion of an electric circuit.

CARL W. RAABE.
